SPOT FACING REAMER

Clifford H. Bennett, Jackson, Mich., assignor to Kent-Moore Organization, Inc., Detroit, Mich., a corporation of Michigan

Application March 26, 1954, Serial No. 418,820

2 Claims. (Cl. 29—103)

This invention relates to reaming tools, and, more particularly, to a spot-facing reamer.

In many of the modern diesel engines of today, the fuel is injected into the combustion chamber by means of a fuel injector device which is mounted in the cylinder head of the engine. An injector nozzle, part of the injector device, opens into the combustion chamber through a port in the cylinder head. Because the injector frequently extends across or through a water-cooling passageway in the cylinder head, it is necessary to seal the water in the passageway from contact with the injector and also prevent leakage of the water from the passageway down along the injector and into the combustion chamber of the engine. To prevent such leakage of water into the combustion chamber around the injector, where the injector enters the combustion chamber, and also to prevent direct contact of the water with the injector, the injector is encased in what may be termed an injector tube.

The tube is made of copper or some other malleable metal. It frequently becomes worn or damaged, or loosens up from its seat in the cylinder head, permitting water to leak into the combustion chamber of the engine. In this event the tube must be replaced. In installing a new injector tube in the cylinder head, to replace a defective one, the tube is placed in the cylinder head to extend across or through the water passageway from the upper surface of the cylinder head to the combustion chamber surface thereof. The tip of the injector tube extends beyond the combustion chamber surface of the cylinder head and is reamed over against the cylinder head to form a water-tight seal between the tube and the head. This flaring operation leaves a certain amount of the tip of the injector tube extending below the surface of the cylinder head. It is desirable to remove this excess portion of the tip of the injector tube so that the tip is flush with the surface of the cylinder head. It is desirable to perform this operation without cutting into the surface of the cylinder head surrounding the tube tip. To remove such excess portion of the tip without cutting into the cylinder head, I have provided the novel spot-facing reamer herein disclosed.

My spot-facing reamer is one tool of a set of injector tube-installation and finishing tools. The set is particularly suited for the removal of a worn or damaged injector tube, the installation of a new tube, and the finishing of the newly installed tube so that it is as serviceable as the injector tubes installed at the factory when the engine was built.

An object of the invention is the provision of a spot-facing reamer which is particularly adapted for the removal of the excess flared end of an injector tube so as to make the tube tip flush with the combustion chamber surface of the cylinder head.

Another object of the invention is the provision of a reamer of the aforesaid character having a smooth surface pilot portion adapted to be inserted in the end of

2

the injector tube to guide the reamer during the spot-facing operation.

Another object is the provision of a spot-facing reamer having radially extending cutting teeth which are relieved along their cutting edges at a determined point so as to form a scraping shoulder adapted to abut the surface of the cylinder head adjacent the tube tip and prevent the reamer from cutting away the metal of the cylinder head.

10 A meritorious feature is the provision of a spot-facing reamer adapted to be mounted in power or hand-operated tool holders, and which reamer is provided with cutting teeth so shaped as to limit the depth to which the reamer may cut during the reaming operation.

15 Advantages of my invention are that: It eliminates the hand-filing of the injector tube tips to make them flush with the cylinder head; it does not require a special drill press but can be operated in a hand tool; time for performing the entire tube tip finishing operation is materially reduced.

Other objects, advantages, and meritorious features will become more fully apparent from the following specification, claims, and drawings, wherein:

Fig. 1 is a cross-sectional view through an injector tube and cylinder head, and showing my spot-facing reamer after the completion of the reaming operation;

Fig. 2 is a perspective view of my spot-facing reamer;

Fig. 3 is an end-view of my spot-facing reamer showing the cutting teeth thereof;

30 Fig. 4 is a cross-sectional view taken on the line 4—4 in Fig. 3;

Fig. 5 is a cross-sectional view taken at the line 5—5 in Fig. 3; and

Fig. 6 is a cross-sectional view through the injector tube tip after it has been flared against the cylinder head and before it has been spot-reamed with my improved reamer.

This invention is intended primarily for use in the finishing of an injector tube tip of an injector tube which 40 has been installed in a cylinder head to replace a worn or damaged injector tube previously removed from the cylinder head. When the new injector tube is installed in the cylinder head to replace the defective one, the tube tip projects beyond the combustion chamber surface of the cylinder head, which surface is indicated in the drawings as 10. The injector tube is indicated as 12 and the tube tip is indicated as 14. The lower end of the tube tip is flared over against the surface 10 of the cylinder head, with the flared-over portion of the tube tip indicated as 16 in Fig. 6. It is necessary to flare

45 over the tube tip to prevent water, or a cooling fluid, which flows through the passageway 18 of the cylinder head 20, from leaking into the combustion chamber by passing around the tube tip. The injector tube, as shown in Fig. 1, extends through or across the water passageway 12 of the cylinder head, and it is obvious that unless provision is made for preventing the water in the passageway from creeping down around the tube and into the combustion chamber, such is bound to occur.

50 The upper end of the tube is sealed against the cylinder head by means of an O-ring type gasket 21, which is seated within a recessed portion 23 of the cylinder head. The tip of the injector tube projects below the surface of the cylinder head through a port 22 formed in the cylinder head. Adjacent the opening of port 22, through the surface 10, the walls of the port are beveled as at 24, and when the tube tip is flared over against the cylinder head, the tube tip is forced outwardly and against such beveled wall of the port 22. As shown in Fig. 6, a certain amount of the tube, after the flaring operation, 55 extends below the surface 10 of the cylinder head. It is highly desirable that this excess portion of the tube

60

tip be removed so that the end of the tube is flush with the surface 10. If the tube tip is permitted to project beyond the surface 10 of the cylinder head as shown in Fig. 6, carbon will tend to accumulate around such tube tip.

Heretofore it has been the practice to remove such excess portion of the tube tip by hand-filing. When the engine is built at the factory and the tubes are installed in the cylinder head, special machinery, similar to a drill press, is used. This machinery is present so that upon its operation it will remove the excess portion of the tube tip, without cutting away any of the surface 10 of the cylinder head surrounding the tube tip. Also, heretofore, various spot-facing reamers have been tried, but in each case, unless the mechanic was extremely careful in the operation of the reamer, he would remove a portion of the cylinder head as well as removing the excess tube tip. After a number of tubes have been installed in a cylinder head over a period of years, if, with each installation, a portion of the cylinder head adjacent the tube tip is removed, eventually the beveled wall 24 of the port 22 will be cut away and the tube tip will not properly seat adjacent the opening of port 22 through the surface 10 of the cylinder head.

My improved reamer shown in various figures includes a body portion 26 and a pilot portion 28. One end of the body 26 is shaped as at 30 to be engaged by a hand or power-operated reamer driving tool. The end 30 of the body is, for this reason, generally square in cross section. The opposite end of the body is generally cylindrical in shape as at 32. The body is axially bored as at 34 to receive the pilot member 28. The pilot is provided with a shoulder 36 adapted to abut the end of the body. The pilot is received within the bore 34 of the body in a press fit. That portion of the pilot projecting beyond the end of the body has a smooth outer surface. The end of the pilot is beveled as at 38 so that it is readily received within the tube tip as shown in Fig. 1.

The end face of the body adjacent the pilot is shaped to provide four radially extending cutting teeth generally indicated as 40. The teeth are separated from each other by radially extending grooves whose walls are indicated at 42 and 50. The cutting edge of each tooth is indicated at 44. The reamer, as viewed in Fig. 3, is turned counterclockwise during the reaming operation. These cutting edges lie on lines projecting radially outwardly from the body. Each cutting edge is formed by relieving or beveling the upper surface of its tooth as at 46, with the high point of the bevel intersecting along edge 44 the side 50 of the tooth. The rearward side of each cutting tooth will be considered as lying in a clockwise direction from each of the cutting edges 44 as the reamer is viewed in Fig. 3. Just to the rear of the relieved portion or bevel 46 of the teeth, they are relieved again as at 48. The relief 48 is at a greater angle of bevel than is the relief 46 as shown in Figs. 2 and 5. The surface 42 rises from the lower edge of the forward side 50 of each tooth to the rear edge of the bevel or relief 48 of the next adjacent tooth. The forward side of each cutting tooth is hooked slightly as at 50, as shown in Fig. 5.

Adjacent the radial extremity of each tooth, it is relieved or beveled as at 52 and 54. The relief 54 of each tooth is circled round and adapted to abut the chamfer 24 of the cylinder head as hereinafter described. The relief 52 is beveled along an angle opposite to the angle of bevel of the relief 46. The relief 52 intersects the relief 46 along the line 56. That portion of the upper surface of the tooth along line 56 forms a scraping edge which is adapted to abut the surface 10 of the cylinder head adjacent the tube tip and prevent the reamer from cutting away any more of the tip after the scraping shoulder abuts the cylinder head. Because of the fact that the relief 52 is beveled on a reverse angle to the

bevel of relief 46, the edge 58 of the relief 52, which forms an extension of the line 44 indicating the cutting edge of the reamer as shown in Fig. 3, is not itself a cutting edge. In other words, the edge 58 of the relief 52 does not cut any metal as the reamer is rotated against the end of the tube tip. The only cutting edge of each tooth is the edge 44, and this terminates at the point of intersection with line 56.

The reason edge 58 is not a cutting edge is that there is always a point on the surface of the relief or bevel 52 that will contact a workpiece before any point along the edge 58 will contact the workpiece. Therefore, the edge 58 is never permitted to contact the workpiece because the surface of bevel 52 will hold the edge away from the workpiece.

The relief 52 intersects the relief 54 along the line 60 as clearly shown in Fig. 3 and viewed in perspective in Fig. 2. Because the reliefs 52 and 54 are beveled in opposite directions, the line 60 is higher than either of the surfaces 52 or 54. Because of the particular shape of the cutting teeth as described hereinabove, when the pilot 28 is inserted in the end of the injector tube, and the cutting edges 44 are brought into contact with the excess portion of the injector tube, such cutting edges will serve to cut away the excess portion of the injector tube tip until the condition shown in Fig. 1 obtains. At this time, the tip of the injector tube has been reamed flush with the surface 10 of the cylinder head. The relief 52 along the line of intersection 56 of the relief 52 and 46 abut the cylinder head and prevent the reamer from cutting to any greater depth. The relief 52 and the line of intersection 56 merely scrape against the cylinder head without cutting it. This is shown in Fig. 1 wherein the cutting edge 44 of the teeth has reached the plane of the surface 10 of the cylinder head. The line of intersection 56 at the point where it meets the cutting edge 44 is in abutment with the cylinder head surface 10 at that point at which the bevel 24 of the port 22 opens through the surface 10. With the line of intersection 56 in abutment with the cylinder head, the reamer cannot be forced to any greater depth than that shown in Fig. 1. After the reaming operation is completed, the reamer is withdrawn from the injector tube.

What I claim is:

45. A spot-facing reamer for use in a tapered port opening through a workpiece comprising: a body member having the rear end adapted to be engaged by a driving tool and the forward end having a face exhibiting a plurality of radially outwardly extending cutting teeth each having its upper face beveled toward a radially extending edge of the tooth to form a cutting edge therealong, the upper face of each tooth adjacent the radial extremity of the tooth being beveled on an angle opposite the angle of the first bevel and inclined radially outwardly and toward the rear end of the body to form a scraping shoulder having a non-cutting edge on the tooth radially outwardly of the cutting edge, said scraping shoulder adapted to abut the tapered wall of the port in conjunction with which the reamer is used to limit the insertion of the reamer in the port.
50. A spot-facing reamer for use in a tapered port opening through a workpiece comprising: a body member having the rear end adapted to be engaged by a driving tool and the forward end having a face exhibiting a plurality of radially outwardly extending cutting teeth each having its upper face beveled toward a radially extending edge of the tooth to form a cutting edge therealong, the upper face of each tooth adjacent the radial extremity of the tooth being beveled on an angle opposite the angle of the first bevel and inclined radially outwardly and toward the rear end of the body to form a non-cutting edge on the tooth radially outwardly of the cutting edge, said beveled portions of the upper surface of each tooth intersecting along a line extending backwardly away from said cutting edge and forming a scraping surface adapted to abut the
55. A spot-facing reamer for use in a tapered port opening through a workpiece comprising: a body member having the rear end adapted to be engaged by a driving tool and the forward end having a face exhibiting a plurality of radially outwardly extending cutting teeth each having its upper face beveled toward a radially extending edge of the tooth to form a cutting edge therealong, the upper face of each tooth adjacent the radial extremity of the tooth being beveled on an angle opposite the angle of the first bevel and inclined radially outwardly and toward the rear end of the body to form a non-cutting edge on the tooth radially outwardly of the cutting edge, said beveled portions of the upper surface of each tooth intersecting along a line extending backwardly away from said cutting edge and forming a scraping surface adapted to abut the
60. A spot-facing reamer for use in a tapered port opening through a workpiece comprising: a body member having the rear end adapted to be engaged by a driving tool and the forward end having a face exhibiting a plurality of radially outwardly extending cutting teeth each having its upper face beveled toward a radially extending edge of the tooth to form a cutting edge therealong, the upper face of each tooth adjacent the radial extremity of the tooth being beveled on an angle opposite the angle of the first bevel and inclined radially outwardly and toward the rear end of the body to form a non-cutting edge on the tooth radially outwardly of the cutting edge, said beveled portions of the upper surface of each tooth intersecting along a line extending backwardly away from said cutting edge and forming a scraping surface adapted to abut the
65. A spot-facing reamer for use in a tapered port opening through a workpiece comprising: a body member having the rear end adapted to be engaged by a driving tool and the forward end having a face exhibiting a plurality of radially outwardly extending cutting teeth each having its upper face beveled toward a radially extending edge of the tooth to form a cutting edge therealong, the upper face of each tooth adjacent the radial extremity of the tooth being beveled on an angle opposite the angle of the first bevel and inclined radially outwardly and toward the rear end of the body to form a non-cutting edge on the tooth radially outwardly of the cutting edge, said beveled portions of the upper surface of each tooth intersecting along a line extending backwardly away from said cutting edge and forming a scraping surface adapted to abut the
70. A spot-facing reamer for use in a tapered port opening through a workpiece comprising: a body member having the rear end adapted to be engaged by a driving tool and the forward end having a face exhibiting a plurality of radially outwardly extending cutting teeth each having its upper face beveled toward a radially extending edge of the tooth to form a cutting edge therealong, the upper face of each tooth adjacent the radial extremity of the tooth being beveled on an angle opposite the angle of the first bevel and inclined radially outwardly and toward the rear end of the body to form a non-cutting edge on the tooth radially outwardly of the cutting edge, said beveled portions of the upper surface of each tooth intersecting along a line extending backwardly away from said cutting edge and forming a scraping surface adapted to abut the

tapered wall of the port in conjunction with which the reamer is used radially outwardly of the cutting edge and limit the insertion of the cutting edge into the work-piece.
